UNITED STATES PATENT OFFICE.

LOUIS E. STONE, OF ASHLAND, KENTUCKY.

AIR-CLEANING DEVICE FOR AUTOMOTIVE MOTORS.

Application filed December 3, 1923. Serial No. 678,357.

To all whom it may concern:

Be it known that I, LOUIS E. STONE, a citizen of the United States, and a resident of Ashland, in the county of Boyd and State of Kentucky, have invented certain new and useful Improvements in Air-Cleaning Devices for Automotive Motors, of which the following is a full, clear, and exact description.

10 The invention relates to a new and improved means for removing the dust from the carburetor air in a highly efficient manner, and one of the objects of the invention is to thus cleanse the intake air and thereby 15 eliminate to a large extent the accumulation of carbon on the cylinders, pistons, and valves.

Another object of the invention is to increase the power and efficiency of the motor 20 by the purification of the air and the consequent elimination of carbon accumulation.

A further object of the invention is to prolong the life of the motor by keeping the same substantially free of carbon at all 25 times.

Still another object of the invention is to produce a smoother operation of the motor resulting from the clean intake air furnished to the carburetor because of its passage 30 through the purifier disclosed herein.

Further objects and advantages of the invention will be apparent from the following detailed description, when taken in connection with the accompanying drawings; in 35 which;

Figure 1 is an end elevational view of the front end of the device.

Figure 2 is a side elevational view of the device.

40 Figure 3 is an end elevational view of the rear end of the device.

Figure 4 is a vertical transverse sectional view taken on line 4-4 of Figure 5; and

45 Figure 5 is a vertical longitudinal sectional view through the complete device.

Referring to the drawings more in detail, numeral 1 indicates a cylindrical casing which is open at both ends, as clearly illustrated in Figure 5. Arranged within this 50 casing and preferably, though not necessarily, extending from end to end thereof is a spiral member or screw 2. The inner wall of the cylindrical casing is entirely free and unobstructed so that the incoming air is allowed to freely follow the spiral course of the screw member.

Arranged centrally of the spiral member and extending therethrough for only a portion of the length of the spiral member, is a pipe 3 leading to the carburetor (not shown). In the drawings I have illustrated the pipe as extending about two-thirds of the length of the spiral member, but obviously this length may be varied as desired, it may be made shorter, or it may be made 60 to extend substantially the full length of the spiral member. At one end of the device, I provide a conical deflector 4, having its apex arranged centrally of, and projecting slightly into, the pipe 3. The function of 70 the deflector is, of course, to reverse the direction of the incoming air, and direct it into the pipe 4, but as will appear herein-after, this deflector may be omitted if 75 desired.

It will be understood, of course, that this device operates on the principle of centrifugal force. Referring particularly to Figure 5, the course of the incoming air is illustrated by arrows, and it will be apparent 80 that as the air strikes the spiral member it will follow the course thereof, and the air thus being set into a rapidly whirling motion, the heavier particles, such as dust, will be thrown outwardly toward the casing 85 wall, and this dust laden air will continue its spiral course through the device and be freely discharged at the rear end, as illustrated by the arrows. In its entire passage 90 there is no obstruction whatever tending to cause the dust to settle, and the dust laden air discharges from the rear end of the device just as freely as it enters the front end thereof.

As the dust laden air centrifugally seeks 95 the outer portion of the device in its passage therethrough, likewise will the pure air centripetally seek the central portion of the device, and as this pure air reaches the end of the pipe 3 it will be drawn therein and pass 100 to the carburetor. Obviously the deflector could be eliminated and the device would function in the same manner but its use does tend to produce a more clear differentiation 105 between the pure and the dust laden air.

The periphery of the screw member is shown as abutting against the casing, but it will be apparent that this is not essential, for the device would operate in the same efficient manner if the screw member were 110 spaced from the wall of the casing. It is not absolutely essential that there be a tight fit

between the pipe 3 and the screw member, but it is highly desirable in order to prevent the direct passage of air along the surface of the pipe 3. The casing, spiral member, and pipe, may all be cast integral, if preferred.

In accordance with the patent statutes, I have described what I now believe to be the best embodiment of the invention, but I do not wish to be understood thereby as limiting myself or the scope of the invention, as many changes and modifications may be made without departing from the spirit of the invention; all such I aim to include in the scope of the appended claims.

Having fully described the invention, what I claim as new and desire to secure by Letters Patent is:

1. The method of purifying the intake air of a carburetor, which consists in passing the air from the front to the rear of a separator, setting the air into whirling motion in the separator, discharging the dust laden air freely to the atmosphere at

25 the rear end of the separator, and causing the pure air to double back through the interior of the incoming column and be discharged at the front of said separator.

2. The method of purifying the intake air of a carburetor, which consists in passing the air from the front to the rear of a separator, causing the air to follow a spiral course through the separator, discharging the outer portion of the whirling column to the atmosphere at the rear end of the separator, and causing the inner portion of the whirling column to double back along the interior of the incoming column and be discharged at the front of said separator.

40 3. In a device of the character described, a casing open to the atmosphere at both ends for the free entrance and exhaust of the air, means for setting the air into a whirling motion, and means for discharging at the front end of the device the inner portion of the whirling column.

4. In a device of the character described, a casing open to the atmosphere at both ends for the free entrance and exhaust of the air, 50 means for causing the incoming air to follow

a spiral course, means for withdrawing the inner portion of the whirling column in a direction opposite to that of the incoming air, and means for discharging the same at the front of the device.

55

5. In a device of the character described, a casing open to the atmosphere at both ends, and the inner wall of said casing being free of obstructions, a spiral member arranged within the casing, and a breather tube arranged within the spiral member for carrying off the pure air.

60

6. In a device of the character described, a casing open to the atmosphere at both ends, and the inner wall of the casing being free of obstructions, a spiral member arranged within the casing, and a breather tube arranged within the spiral member for carrying off the pure air, said breather tube terminating short of one end of the spiral member.

65

7. In a device of the character described, a casing open to the atmosphere at both ends, and the inner wall of the casing being free of obstructions, a spiral member arranged within the casing, and a deflector arranged at one end of the spiral member for deflecting the inner portion of the whirling column into the interior of the spiral member.

75

8. In a device of the character described, a casing open to the atmosphere at both ends, and the inner wall of the casing being free of obstructions, a spiral member arranged within the casing, a breather tube arranged within the spiral member, and a deflector arranged to deflect the inner portion of the whirling column into the breather tube.

80

9. In a device of the character described, a casing, means within the casing for forming the air into a spiral column moving from the front to the rear of the casing, said casing having at the rear end a free exit to the atmosphere for the outer portion of the column, and means for carrying off the air from the inner portion of the column and discharging the same at the front of the device.
